JOHN J. MURPHY, OF SAN FRANCISCO, CALIFORNIA.

ICE-MAKING MACHINE.

1,160,945.

Specification of Letters Patent. Patented Nov. 16, 1915.

Application filed September 28, 1914. Serial No. 863,867.

To all whom it may concern:

Be it known that I, JOHN J. MURPHY, a citizen of the United States, residing in the city and county of San Francisco and State 5 of California, have invented new and useful Improvements in Ice-Making Machines, of which the following is a specification.

This invention relates to an ice making machine.

10 All of the clear, pure ice manufactured today for household uses and the like is made from condensed steam. Clear ice is also produced from raw water agitated by compressed air which is forced through a pipe 15 submerged in the water. At present this is partly accomplished but is limited by the fact that the tube delivering the air below the water surface must be withdrawn before solidification is complete, leaving a cloudy 20 core from the water solidified after agitation has ceased.

It is one of the objects of the present invention to provide a simple attachment whereby the pipe will be automatically withdrawn as the ice forms, or, in other words, 25 to continue agitation within the receptacle until solidification has been completed.

Another object of the invention is to provide a pneumatically actuated mechanism 30 whereby the air will be distributed and the pipe automatically lifted.

Further objects will hereinafter appear.

The invention consists of the parts and the construction and combination of parts 35 as hereinafter more fully described and claimed, having reference to the accompanying drawings, in which—

Figure 1 is a central, longitudinal section through the machine or apparatus. Fig. 2 40 is a plan view of same. Fig. 3 is a cross section on line 3—3, Fig. 2.

More specifically described, A indicates an ordinary freezing tank filled with brine, or like solution, which is kept at a freezing temperature by means of ammonia pipes, or the like, in the usual manner. Mounted in tank A and filled with the water to be frozen is a tank B, and extending down into said tank is a pipe 2 through which the air is delivered. Pipe 2 is mounted in a guide bracket 3 and is adapted to be slowed reciprocated by means of a clutch 4 carried in

the outer end of an arm 5, centrally pivoted, as at 6, on a standard 7. The other end of the arm is connected, as at 8, with the piston rod 9 of an air motor generally indicated at 10, which is constructed and operated as follows:

11 and 12 indicate a pair of convex shaped casings which are clamped together by 60 means of bolts or screws 13. Interposed between said casing sections is a flexible diaphragm 14, and secured to said diaphragm, by means of plates 15, is the piston rod 9.

Air is alternately admitted and exhausted 65 on each side of the diaphragm 15 by means of a three-way valve 16. Air under pressure is admitted to the lower side of the valve, at 17, by a pipe 18 and is from here directed by a port 19, formed in the plug 20, to one 70 or the other of a pair of pipes 21 and 22; pipe 21 being connected with the upper casing 11 while the lower pipe 22 is connected to the lower casing 12. Live air admitted at 17 and passing through the port 19 will pass 75 out through the pipe 21 and into the upper casing 11. This will force the diaphragm downwardly and will at the same time permit the air in the lower side of the casing to exhaust through the pipe 22. This forces 80 the piston rod 9 in a downward direction, transmitting a rocking movement to arm 5.

Mounted on arm 5 is a pin 23 which is adapted to engage with a quick acting valve 85 lever 24. This lever is connected by means of a link 25 with a lever 26 secured to the valve plug. A slight contact of the pin 23 with the lever 24 will move this into a position where a spring 27 connected therewith will turn it quickly from one side of the center 6 to the other. This quick throw of movement of the lever from one side of center 6 to the other will be transmitted, through the link 25 and arm 26, to throw the valve plug in the direction of arrow a where 90 port 19 will be moved out of register with the connection 17 and into register with an exhaust port 28. A cutaway portion 29 on the valve will then form communication between pipe 21 and the exhaust connection 28. 100 A port 19 will, at the same time, be thrown into register with the connection 17 and will permit the air under pressure to pass through the pipe 22 into the lower side of

the casing, forcing the diaphragm in an upward direction. The air previously admitted through pipe 21, on the upper side of the casing, will then be permitted to exhaust through pipe 21, by-pass 29 and exhaust port 28 to a pipe 30 which is connected by means of a flexible hose 31 with the upper end of pipe 2. A complete upward movement of the flexible diaphragm, caused by the admission of air into the lower side of the casing through pipe 22, will similarly transmit movement through the piston rod 9 to move arm 5 in an upward direction. The pin 23 will now engage with an upper shoulder formed on the quick acting valve lever 24 and will move it into a position where the spring 27 will throw it into the opposite direction, moving the plug in a direction opposite to that indicated by arrow *a*. Port 19^a will now be thrown into exhaust position, while port 19 is moved into intake position.

The operation of the flexible diaphragm, with connected valve mechanism, is thus continuous and automatic and the reciprocal movement is transmitted to pipe 2. The air used in connection with the flexible diaphragm, when exhausted by valve 16, is conveyed through the flexible hose 31 to the reciprocal pipe 2. All the air is thus used and not wasted. Part of the air under pressure may be passed directly through the hose 31, if the exhaust air from the diaphragm does not prove to be sufficient. This is accomplished by placing a valve 32 in an intermediate position between pipes 30 and 18. Air under pressure may thus be passed directly from pipe 18, through valve 32 and pipe 30, into the flexible hose 31, with connected pipe 2. The speed of reciprocation or movement of the diaphragm may also be controlled by valve 32, as the adjustment of same will cause more or less air to pass directly to the pipe without passing through the casing and diaphragm. The exhaust from pipe 22, passing through the by-pass 29^a, is exhausted through a pipe 33 which is in turn connected with pipe 30 and the flexible hose connection 31.

In operation, the moment the water within tank B becomes partly frozen it will be seen that the reciprocal movement of pipe 2 will in time bring it into contact with the bottom ice. The clutch 4 will then slide down on the pipe and permit the pipe to rest on the ice. The upward movement of arm 5 and clutch 4 will again pick up the pipe and keep it reciprocating until it again strikes the ice as it is gradually formed. The pipe is thus automatically and gradually withdrawn as the ice forms and agitation of the water subjected to the freezing temperature is continued until the contents has become completely solidified.

The present device eliminates a steam producing plant, condensers, cooling systems,

etc. It also eliminates the water waste and minimizes the labor used in connection with a large plant.

The term "raw water" used in the specification means water which has not been through the condensing process. It may, however, be filtered or otherwise treated.

Having thus described my invention, what I claim and desire to secure by Letters Patent is—

75

1. The combination with the freezing tank of an ice making machine, of an air delivering pipe extending into the water contained in the tank, an air motor, an arm adapted to be rocked by said motor, and a clutch carried by said arm in which the air delivering pipe is mounted.

80

2. The combination with the freezing tank of an ice making machine, of an air delivering pipe extending into the water contained in the tank, an air motor, an arm adapted to be rocked by said motor, a clutch carried by said arm in which the air delivering pipe is mounted, an air valve interposed between a source of supply and the motor, and means controlled by the rocker arm for turning the valve to deliver and exhaust air in the motor.

85

3. The combination with the freezing tank of an ice making machine, of a pipe extending down into said tank, means for delivering air to the pipe and forcing it through the water contained in the tank, means for automatically withdrawing the pipe as the water freezes, said means comprising a clutch by which the pipe is carried, and means for reciprocating said clutch, said means including a centrally fulcrumed lever one end of which actuates the clutch and an air motor with which the opposite end of the lever is connected.

95

4. In a machine of the character described a freezing tank, a pipe extending vertically into said tank, means to withdraw said pipe as the water freezes, said means including a clutch slideable upon the pipe, a fulcrumed lever one end of which engages the clutch to cause it to bind on and raise the pipe and to allow it to slip freely in the opposite direction a reciprocating rod connected with the opposite end of the lever and a motor connected with the opposite end of the rod.

100

5. In a machine of the character described, a freezing tank, an air conducting pipe extending vertically into the tank, means to inject air into the pipe said means including a casing with a diaphragm fixed at the edges, pipes connecting with the casing at opposite sides of the diaphragm, an oscillating valve with the case of which said pipes connect and to which air under pressure is supplied, a pipe connecting said valve chamber with the connecting pipe of the freezing tank, a lever reciprocated by the movements of the diaphragm and a clutch actuated by said lever.

105

110
